UNITED STATES PATENT OFFICE.

LAWRENCE C. COTNER, OF LOS ANGELES, CALIFORNIA.

DESIGN FOR A SHINGLE.

Application filed February 23, 1928. Serial No. 25,546. Term of patent 14 years.

To all whom it may concern:

Be it known that I, LAWRENCE C. COTNER, a citizen of the United States, residing at Los Angeles, in the county of Los Angeles, and State of California, have invented a new, original, and ornamental Design for Shingles, of which the following is a specification, reference being had to the accompanying drawing, forming part thereof.

The figure is a plan view of a shingle, showing my new design.

I claim:

The ornamental design for a shingle, as shown.

In testimony whereof I affix my signature.

LAWRENCE C. COTNER.
